UNITED STATES PATENT OFFICE.

WILLIS P. CARRUTHERS, OF OBERLIN, OHIO.

BASE-BALL SCORING DEVICE.

1,038,289.

Specification of Letters Patent. Patented Sept. 10, 1912.

Application filed August 3, 1910. Serial No. 575,211.

To all whom it may concern:

Be it known that I, WILLIS P. CARRUTHERS, a citizen of the United States of America, residing at Oberlin, in the county 5 of Lorain and State of Ohio, have invented certain new and useful Improvements in Base-Ball Scoring Devices, of which the following is a specification, reference being had therein to the accompanying drawing.

- 10 This invention relates to pocket devices for indicating the relative standing of baseball teams in a league, and the principal object of the same is to provide a pocket indicator by means of which the percentage of 15 victories may be readily changed according to the daily scores so that an absolutely accurate record may be had and retained in a pocket so that the same may be accessible when desired.
- 20 In carrying out the objects of the invention generally stated above, it will be understood, of course, that the essential features thereof are necessarily susceptible of changes in details and structural arrangements, preferred and practical embodiments of which 25 are shown in the accompanying drawings, wherein—

Figure 1 is a top plan view, partly in section, of the improved indicator. Fig. 2 is a 30 part section and part side elevation taken substantially on the line 2—2, Fig. 1. Fig. 3 is a transverse vertical sectional view taken on the line 3—3, Fig. 1. Fig. 4 is a detail fragmentary view of a modification of the 35 invention.

Referring to said accompanying drawings by numerals, 1 designates the flat casing of the improved score indicator which is preferably rectangular in shape and is provided 40 with a partition 2 that divides the interior of the casing into a narrow compartment 3 and a wide compartment 4. The cover 5 of the casing is provided with a longitudinal row of regularly-spaced slots 6 which are 45 formed in the cover over compartment 3. Said cover is also provided with three longitudinal rows of openings 7, 8, 9 which are arranged over compartment 4. It will be observed that the openings 6, 7, 8 and 9 50 are all formed so that they flare outwardly. By means of this arrangement, a superior and uninterrupted view is given of the counters beneath. Furthermore, this flaring arrangement also prevents the throwing of 55 any shadow on the counters or indicators. The openings of said rows 7, 8, 9 correspond

in number and are in alinement with the slots 6. Casing 1 has its side adjacent compartment 3 provided with a longitudinal recess 10 and the bottom of said casing beneath 60 compartment 4 and at a point in alinement with the openings 9, is also provided with a longitudinal recess 11. A horizontal shaft 12 is journaled in the side walls of compartment 3 below each slot 6, said shafts 65 projecting into recess 10 and provided with finger grips 13 in the form of a milled disk by means of which said shafts may be manually rotated. Each shaft has a drum 14 fast thereon, the surface of which contains the 70 names of the baseball teams, said names being arranged on the drums so that by rotating the drums the name of any one team may be viewed through the slot 6 over the same.

The bottom of the casing is provided with three rows of vertical shafts 15, 16 and 17, said shafts corresponding in number with the rows of openings, 7, 8, 9. The shafts 17 75 each project through the bottom of casing 1 and enter recess 11 and are provided with a finger grip 18 by means of which the same may be manually rotated. The upper end of shafts 17 have a disk 19 thereon, the periphery of which is provided with two 80 teeth 20. Said disks rotate across openings 9 and are provided with numerals running from 0 to 9 which may be viewed one at a time through said openings. Shafts 16 at their upper ends carry two disk sections 90 21—22. Disks 21 are provided with twenty peripheral teeth 23 which are engaged by teeth 20 of disks 19. Said disks 21 rotate across openings 8 and are provided with numerals running from 0 to 9 which may be 95 singly viewed through said openings 8. Disks 22, which are below disks 21, are provided with two teeth 24 on their peripheries which are engaged by teeth 20 of disks 19. Shafts 15 at their upper ends carry two disk 100 sections 25—26. Disks 25 are provided with two peripheral teeth 27 which are engaged by the teeth 23 of disks 21. Said disks 25 rotate across openings 7 and are provided with numerals running from 0 to 9 which may be singly viewed through said openings. Disks 26 are provided with twenty 105 peripheral teeth 28 which are engaged by the teeth 24 of disk 22.

It will now be noted that because of the 110 arrangement of the numeral bearing disks so that some of these disks lie close to the

face of the casing while others are more remote therefrom, the peculiar flaring openings are of great value since they enable the numerals on the remote counters to be seen 5 as clearly as those on the counters which are close to the face of the casing. It will also be noticed that the arrangement of the recesses 10 and 11 prevents any accidental derangement of the counters or indicators 10 so that the scores will remain undisturbed unless intentionally changed.

The improved indicator is arranged for showing at a glance the relative standing of the teams of an eight club league, and from 15 the foregoing description it will be understood that drums 14 may be rotated so the clubs may be arranged in a vertical row according to their standing. It will also be seen that the three rows of openings 7, 8, 9 20 provide three openings in alinement with each opening 6 so that the percentage of each club may be displayed, the disks 19, 21 and 25 which carry the percentage numerals being in meshed engagement so that they 25 may be readily rotated to indicate different percentage numerals in accordance with the changes in the standing of the clubs due to 30 games won or lost. For example, it will be seen that the disks 19 being provided with 35 but two teeth, and the disk 21 being provided with twenty teeth, disks 19 will be compelled to make one complete rotation to cause disks 21 to move one figure, and in a like manner disks 21 will be compelled to make one complete rotation to move disk 25 one figure.

In Fig. 4, a modification of the invention 40 is suggested which consists in employing flat disks 29 in place of the drums 14. Said disks are mounted on the shaft 30 which extends into a longitudinal base recess 31 of bottom 1 and are equipped with a finger

grip 32. In this form of the invention, the names of the clubs are arranged around the edge of the disks and are displayed through 45 the slots 33 of body 1, said slots being curved.

What I claim as my invention is:—

In a device of the kind described, a casing including a front member provided with a 50 plurality of series of outwardly flaring openings, said casing being further provided with a plurality of recesses, one of said recesses extending throughout the length of one side of the casing and the remaining recess extending throughout the length of the bottom of said casing, a series of indicators held to rotate within said casing adjacent the side recesses and beneath one series of openings, a series of thumb nuts operatively 55 connected to said indicators and lying wholly within said side recesses whereby the heads of said nuts are prevented from contact with external objects, a plurality of series of counters each having numerals thereon 60 adapted to show through one of the remaining openings, said counters alternately overlapping and underlying each other whereby certain of said counters lie close to the front of said casing and the remainder of said 65 counters are more remote therefrom, and a series of thumb nuts operatively connected to said counters and lying wholly within the recesses in the back of the casing, whereby 70 said casing may be laid upon an object without said thumb nuts coming in contact therewith.

In testimony whereof I hereto affix my signature in presence of two witnesses.

WILLIS P. CARRUTHERS.
